UNITED STATES PATENT OFFICE

EDWARD N. SONNENBERG, OF BROOKLYN, NEW YORK

DESIGN FOR A TEXTILE FABRIC

Application filed April 5, 1930. Serial No. 35,173. Term of patent 3½ years.

To all whom it may concern:

Be it known that I, EDWARD N. SONNENBERG, a citizen of the United States, residing in the borough of Brooklyn, Kings County, city and State of New York, have invented a new, original, and ornamental Design for Textile Fabrics, of which the following is a specification, reference being had to the accompanying drawing, forming part hereof.

The figure of the drawing is a plan view of a piece of textile fabric embodying my design, a repeat unit of which is included between the crosslines indicated on the drawing. The extensions beyond the unit area indicate its relation to the preceding and succeeding units.

The design consists of a plurality of short diagonal lines, of varying size, having wide bases, which taper or are stepped down to a narrow apex, pointing in an upward direction. These lines are interspersed between longer and thicker zig-zag lines. These zig-zag lines appear in rows of parallel zig-zag lines, the alternate rows pointing in the same direction.

What I claim is:

The ornamental design for a textile fabric, as shown and described.

In witness whereof, I have signed my name to this specification, this 1st day of April, 1930.

EDWARD N. SONNENBERG.
